D. H. GREEN

EMERGENCY CONTROL VALVE

Filed Sept. 18, 1922

INVENTOR.

David H. Green

BY

M. C. Frank
ATTORNEY.

UNITED STATES PATENT OFFICE.

DAVID H. GREEN, OF SAN FRANCISCO, CALIFORNIA.

EMERGENCY CONTROL VALVE.

Application filed September 18, 1922. Serial No. 588,835.

To all whom it may concern:

Be it known that I, DAVID H. GREEN, a citizen of the United States, residing at San Francisco, in the county of San Francisco and State of California, have invented a new and useful Emergency Control Valve, of which the following is a specification.

This invention relates in general to improvements in emergency-control valves, and 10 in particular to a method and apparatus for controlling the flow of gas or oil from oil wells.

Flowing oil wells are encountered in nearly every oil field of importance, and are 15 often of such violence as to completely destroy the rig and surroundings. Where a heavy flow is unexpected, and no preparations for capping have been made, to gain control is exceedingly difficult, often impossible. When a stream of oil is shooting into the air, there is naturally a heavy loss especially of the lighter and more valuable oils. To prevent this, the present method is to place boiler shells upon skids, or heavy timbers reinforced with steel plates are drawn 20 over the hole at the derrick floor and prevented from being thrown off by wire slings anchored to the derrick sills.

Occasionally a flowing well takes fire, and 30 to extinguish the blaze is a difficult matter and often impossible. Great quantities of steam are often successful in snuffing out fires, sometimes chemicals, and at times tunneling below the surface is resorted to, to 35 squeeze the casing together by jacks.

So far as I am aware, there is nothing on the market or in use, attachable to the well that can cope with fire and be controlled from afar.

40 The main objects of the invention are, to control the well from a remote safe distance to shut it off, or seal it, when it "comes in," or at other times, and in case the issuing gas or oil takes fire, to shut it off and thereby 45 extinguish the fire.

I attain the above objects by applying a special fitting to the top of the well casing. This fitting includes a screening means adapted to arrest rocks, gravels, sand, etc., 50 thrown up by the spouting well, also, a means for impeding the stream of oil to get the benefit of its vis viva, and diverting a portion thereof into a lateral pipe, which pipe may extend to a safe and remote distance from the well, and there, be provided 55 with a valve by which the oil may be di-

rected against a piston, or plunger, and thereby move a closure across the outlet of the well and seal the same. The apparatus also includes means for reopening the said 60 outlet by moving the said closure back to its normal position.

In addition to the above broader features of the invention, there are certain details of design, whereby compactness, simplicity and 65 durability of structure, as well as positiveness and ease of operation are obtained, and which are shown in the drawings, and the essentials thereof will be set forth hereinafter.

70 In the accompanying sheet of drawings, I have illustrated an apparatus containing my invention in its best form.

Figure 1 is a partial longitudinal sectional elevation of the apparatus, showing 75 the closure partly across the well outlet.

Figure 2 is a plan view of the apparatus of Figure 1, and shows in addition, the remote control means, and the screw to operate the closure in one direction.

Figure 3 is a partial end elevation and partial vertical section, showing the screen and the pipe leading therefrom for transference of the vis viva energy.

Figure 4 is a cross-section at A—A of 80 Figure 3, through the channel and looking in the direction of the arrows.

Referring to the drawing and the figures thereon: 1 represents the top of a well casing, and 2 a flange coupling thereon. 3 is 90 a flange on my special fitting, adapted for coupling to flange 2 by bolts, as shown. Above the circular opening 4 into the apparatus, is a smaller circular opening 5, formed by a conical channel 6, facing downward 95 and having a rounded bottom, into which some of the gushing oil is directed through the screen openings 7. The rounded bottom of the channel partially reverses the direction of the oil entering therein, and directs it into the main discharge, impeding somewhat the flow of the oil.

Opening from the channel 6, is a pipe 8, so situated as to take oil from the channel by virtue of the direct and increased pressure, caused by the vis viva of the spouting stream, as in a Pitot tube. The pipe 8 may extend from the well to a safe distance, and be there, controlled and returned upon itself and connect with the end of a cylinder 9, which constitutes a part of my special fitting. In the cylinder 9 is a piston 10

having a plunger 11, and which plunger is of larger diameter than the well outlet, and, being moved across the latter, constitutes an effective closure therefor.

5 12 is a sediment trap in the pipe 8. The orifice 13, through which the oil passes from pipe 8 into the cylinder 9, may be considerably reduced, as seen in Figure 1, to guard against a too sudden movement of the

10 plunger. As a further guard against a too

sudden closure of the well, the end of the plunger is beveled as at 14, and to prevent the plunger rotating in its socket, it is provided with a fin 15 which maintains its

15 parallelism by reason of the outflowing oil.

As the piston 10 is usually of a larger diameter than the closing plunger 11, a drain 16 is provided to relieve the space 17 from entrapped oil or air pressure. As the plunger

20 11 completes its closing movement, its end enters a continuation of its socket at 18.

The space 18 is provided with a drainage means at 19, to relieve it of entrapped oil.

At the end of the cylindrical space 18 in

25 which the plunger seats, I provide a screw

20, which may act against a boss 21 on the plunger, to push the latter to its normal open position when it is desired to again open the well.

30 At a convenient and remote point on the pipe line 8, out of danger from the spouting oil, is a valve 22 which manually controls

the flow of oil through the pipe to the cylinder 9. In reopening the well, the valve 22

35 is closed, and a drainage means as at 23,

opened to relieve the pressure behind the piston 10.

30 Lateral openings as at 24, may be provided for pipe connections leading to storage tanks

40 to relieve the well pressure should it be deemed advisable to do so after the plunger has sealed the well.

45 25 is a flange having standard drilling, and adapted to receive any standard fitting desired, to lead the outflowing oil to the storage tanks.

Having thus illustrated and described my invention in its preferred form, I wish it understood that the same may be modified

50 from time to time as practice suggests. Therefore, the patent protection that I desire, is all of that which comes within the spirit and scope of the invention as claimed.

I claim:

55 1. An oil well closure operable by the force of its moving stream of oil and adapted to be controlled manually and from afar by a valve through which a portion of the oil passes.

60 2. An oil well closure, operable by the

vis viva of its moving stream of oil and adapted to be controlled manually and from afar by a valve through which a portion of the oil passes.

3. An oil well sealing apparatus manually 65 controlled from afar by valve means, comprising a plunger adapted to be projected across the well and seal the same, and means for retracting the said plunger to reopen the well.

4. An oil well closure manually controllable from afar by valve means, comprising a cylinder and a piston therein, deflecting means for turning a portion of the oil into the said cylinder for moving the said piston 75 across the well to close and seal the same.

5. An oil well sealing apparatus, comprising means for deflecting the stream of oil, means for drawing off a portion of the said oil at the point of deflection into a pipe, 80 means for controlling the movement of the said oil in said pipe, said last named means located at a safe distance from the well, and means operated by the oil from said pipe for operating a closure for said well. 85

6. An oil well sealing apparatus, having an inverted channel with a rounded bottom, said channel adapted to receive oil from the well and deflect it back upon itself, a pipe connected with said channel at the point of 90 deflection and adapted to receive oil therefrom and deliver it to a closure operating means.

7. An oil well sealing apparatus, having a peripheral screen about the oil exit from the 95 well, a peripheral conical channel adapted to receive oil through said screen and direct it back upon itself, and a closure operated by oil delivered from said channel.

8. In an oil well closure, a plunger, a 100 cylinder therefor, the plunger provided with a head of larger diameter than the body of the same, and means for turning a portion of the oil from the well into said cylinder behind the enlarged head of the plunger to move the latter across the well to close and seal the same.

9. In an oil well closure, a plunger, a cylinder therefor, an enlarged head on the plunger, and a pipe connected to the cylinder to turn a portion of the oil from the well into the cylinder and behind the enlarged head of the plunger to move the latter across the well to close and seal the same, said pipe extending exteriorly of the cylinder and a valve in said pipe for controlling the flow of oil therethrough. 110

In testimony whereof I affix my signature.

DAVID H. GREEN.
